H. L. PIERCE.
AEROPLANE.
APPLICATION FILED OCT. 30, 1919.

1,344,314.

Patented June 22, 1920.

UNITED STATES PATENT OFFICE.

HARRY L. PIERCE, OF EAST DOWNTONTOWN, PENNSYLVANIA.

AEROPLANE.

1,344,314.

Specification of Letters Patent. Patented June 22, 1920.

Application filed October 30, 1919. Serial No. 334,455.

To all whom it may concern:

Be it known that I, HARRY L. PIERCE, a citizen of the United States, residing at East Downingtown, in the county of Chester, 5 State of Pennsylvania, have invented certain new and useful Improvements in Aeroplanes; and I do hereby declare the following to be a full, clear, and exact description of the invention, such as will enable others 10 skilled in the art to which it appertains to make and use the same.

This invention relates to new and useful improvements in aeroplanes.

One object of the present invention is to 15 provide a novel and improved aeroplane wherein provision is made for the pilot in the forward portion of the fuselage and for the gunner in the tail of the aeroplane.

Another object is to provide novel and 20 improved means whereby the weight of the gunner and gun, in the tail of the aeroplane will not interfere with the proper operation and guiding of the machine, and whereby a following enemy can be taken care of without 25 the pilot having to take his attention from the operation of the machine, or necessitate the turning of the machine to meet or make an attack.

Other objects and advantages will be apparent 30 from the following description when taken in connection with the accompanying drawing.

In the drawing:

Figure 1 is a side elevation of an aeroplane 35 made in accordance with my invention.

Fig. 2 is a top plan view of the same.

Referring particularly to the accompanying drawing, 10 represents the fuselage of 40 the aeroplane which has the upper and lower main sustaining planes 11 supported on the front end thereof, with the seat 12 for the pilot and all of the proper controls for the different mechanisms by means of which the

aeroplane is guided upwardly and downwardly, or maintained on an even keel. Carried by the rear end or tail of the fuselage are the shorter upper and lower sustaining planes 13, and in this portion of the fuselage is arranged the seat 14 for the gunner and 45 his gun. Hinged to the rear end of the fuselage is the elevating rudder 15. Secured to the upper side of the rear portion of the fuselage, in advance of the gunner's seat, is the vertical longitudinal fin 16, and hinged 50 to this fin is the horizontally swinging rudder 17.

By this construction the weight of the gunner and his gun, in the tail end of the fuselage, are properly supported and balanced 55 by the rear sustaining planes, thus relieving the pilot of the labor of watching the movements of the gunner and of enemy planes which might be following with the intention of attacking from the rear. 60

The forward portion of the fuselage is supported by the wheeled running gear 18, while the rear end is supported by the 65 wheeled running gear 19.

What is claimed is:

An aeroplane comprising a fuselage having front upper and lower sustaining planes and a pilot's seat therebetween, a vertical fin on the rear portion of the fuselage, a vertical rudder mounted on the fin, an elevating rudder mounted on the rear end of the fuselage, and upper and lower sustaining planes mounted on the fuselage between the vertical rudder and the elevating rudder, and a gunner's seat between the rear sustaining planes. 70 75 80

In testimony whereof, I affix my signature, in the presence of two witnesses.

HARRY L. PIERCE.

Witnesses:

Wm. C. HANNUM, Jr.,
GEO. F. CUNNINGHAM.
